UNITED STATES PATENT OFFICE.

FRANK E. HARTMAN AND HARRY BUXTON HARTMAN, OF SCOTTDALE, PENNSYLVANIA, ASSIGNEES TO ELECTRIC WATER STERILIZER & OZONE COMPANY, OF SCOTTDALE, PENNSYLVANIA, A CORPORATION OF PENNSYLVANIA.

PROCESS FOR SOFTENING WATER.

Application filed March 21, 1922. Serial No. 545,508.

To all whom it may concern:

Be it known that we, FRANK E. HARTMAN and HARRY B. HARTMAN, citizens of the United States, residing at Scottdale, in the 5 county of Westmoreland and State of Pennsylvania, have invented certain new and useful Improvements in Processes for Softening Water, of which the following is a specification.

10 This invention relates to a novel process for more thoroughly and expeditiously softening water.

To that end the invention has primarily in view the acceleration of the softening process by assisting chemical reaction through the action of an electrolytic cell, that is, by electrolysis, which, if not actually increasing the ionization at least accelerates the reaction between the ions and by the 15 speed of reaction thus obtained rapidly carries the process to completion without the addition of appreciable excesses of precipitating reagent which frequently results in rendering the water alkaline. Accordingly, 20 it will be apparent that the process contemplated by the present invention generally involves the use of an electrolytic cell to obtain the benefits of highly ionized solutions thus to obviate the necessity of resorting to 25 the usual practice of utilizing an excess amount of precipitating reagent to effect the completion of the reaction.

Primarily therefore the invention has in view to obtain a highly ionized solution, or 30 in other words, proposes to predispose the water to rapid reaction by the influence of electrolysis and to that end combines with the chemical process an electrolytic step which may be performed at any suitable or convenient point in the process according to 35 the character of the chemical reactions involved. In all cases however, the electrolysis is accomplished at the most advantageous point to effect maximum ionization.

40 Obviously the process may be practiced by any suitable and convenient type of apparatus, but for purpose of illustration, the accompanying drawings show more or less diagrammatically the general organization 45 of instrumentalities involved. In the drawings:

Figure is a plan view of an improved plant for carrying out our novel process.

Fig. 2. is a side elevation thereof, and

Fig. 3 is a diagrammatic view, in section, 55 of the electrolytic cell used in the process.

Similar reference characters designate corresponding parts throughout the several figures of the drawings.

It is a well known fact that natural waters 60 are hard or soft according to their origin and the chemical character of the soils with which they contact and in the case of the so-called hard waters it is desirable as well as necessary to subject the same to so-called 65 softening processes for rendering them better adapted to home as well as industrial use. The so-called hard waters are due to the presence of the bi-carbonates of calcium and magnesium together with the chlorides, 70 sulphates and nitrates of the same basis and the hardness is usually of two kinds, temporary and permanent. The bicarbonates constitute what is known as the temporary 75 hardness while the chloride, sulphate and nitrate constitute the permanent hardness.

Temporary hardness may be dispelled by boiling or by the use of suitable quantities of lime, while the permanent hardness caused by the salts of calcium and magnesium is usually removed by the use of soda ash or Na_2CO_3 as the reagent. It will therefore be apparent that the softening of 80 water depends upon chemical reactions between the reagents and the offending salts contained in the water.

In inorganic chemistry all reactions can be said to be trimolecular, that is, a third substance is necessary to facilitate the reaction between the two other substances. This third substance is in most cases either an 85 aqueous vapor or water which accelerates the velocity of chemical reactions by acting as an electrolyte. Going a step further and examining the electrolytic dissociation theory it is found compounds that do not respond in every respect to osmotic pressure laws, will when dissolved in water dissociate, or partly dissociate into their ions. 90 From observed phenomena, it appears that compounds are infinitely more active when dissolved in water and we may therefore rightly infer that they are more active in the ionic state.

Also in the softening of water there is another factor relating to the velocity of 105 reaction that must be taken into consideration, namely, the law of mass action which is

briefly defined—that the amount of chemical action is proportional to the active mass of each of the substances reacting, active mass being defined as molecular concentration of the reacting substances. That is to say, if equivalent amounts of two given chemicals are prepared for combination the reaction will proceed until a certain percentage of the reacting substances have been used up and then the reaction comes to a standstill. It will therefore be seen that an excess amount of precipitating agent must be employed to complete the precipitation of the substance in solution, and it is for this reason that an excess of the reagent is always used in analytical chemistry.

In the softening of water however it is desirable to avoid the use of large excess of reagents since by so doing the softened water is rendered alkaline although perhaps the hardness forming salts have been eliminated.

Accordingly, it appears that the best reaction takes place between ionized salts, and that the reaction proceeds according to the mass participating. The usual way of accelerating the completion of the reaction by the use of an excess of precipitating agent is not desirable for the reasons heretofore given and therefore to obtain complete and effectual reaction in a water softening process the present invention proposes to utilize highly ionized solutions. As it has been found in practice that salts are much more active under the influence of electrolysis, it follows that the presence of electrically charged bodies at least accelerate reaction between the ions if not actually increasing the ionization, and since the presence of other ions does not retard the ionization of the reacting salts in solution it appears that the speed of reaction is greatly increased and by such speed the reaction is carried to completion without necessitating the addition of appreciable excesses.

Therefore, in carrying forward the objects of the present process it is proposed to predispose the water into rapid reaction by the influence of electrolysis, the electrolytic action taking place either before the water enters the electrode chamber or after it passes from the electrode chamber and before it enters the sedimentation chamber.

The accompanying drawings illustrate a type of chemical water softening apparatus designated generally as A' with which it is proposed to combine the electrode box or electrolytic cell B of the type, for example, shown in the patent to H. B. Hartman, No. 1,101,278, the same being arranged posterior to the point of chemical reagent supply according to the arrangement shown but it will of course be understood, as heretofore pointed out that this cell may be placed anterior to the point of chemical

reagent supply in which event the chemical reagent would be supplied through the pipe line x, shown in dotted lines in Figure 2. In this connection it will be understood that the introduction of the chemical reagent into the line of passage of the water with reference to the cell B will largely depend upon the character of the various intermediate reactions likely to be encountered under different circumstances. In all cases however, the function of the electrolytic cell will be to predispose the water into intermediate reaction and at the same time produce a coagulant.

Referring more in detail to the drawings, 5 represents the influent pipe which conveys the water to the purifying plant. Located at intervals along this pipe are jet mixers 6 and 7 by means of which reagents such for example as used in the well known Porter-Clark process may be mixed with the raw water. These chemicals are introduced by pipes 8 and 9 which are respectively provided with controlling valves 8^a and 9^a. The jet is employed for preventing back pressure in either or both of the pipes 8 and 9, as such a back pressure might prevent or retard the proper flow of the solutions.

The water thus treated, passes through a valve 10 and thence through an inlet pipe 11 to the electrolytic cell B. This cell or unit comprises top and bottom plates 13 and 14 which are held together by bolts 15. A plurality of electrode plates 16 of iron or other suitable material and of bipolar construction are disposed between said plates 13 and 14. The electrode plates are separated by spacing gaskets 17 having openings 18 for the upward passage of the water, and openings 19 for the downward passage of the water after it has passed all of these electrodes in a tortuous path, said water proceeding through the discharge pipe 20 and control valve 21 thereof. The water then passes into a stand pipe 22 of a sedimentation tank 23 which has a sufficient surface to permit the deposition of precipitates during the flow of the water through it towards the outlet or overflow pipe 24. In order to prevent the direct passage of water from the stand pipe 22 to the overflow pipe 24, a partition or baffle 25 is employed in said tank. The water passes from the overflow pipe 24 through a pipe 26, having controlling valves 27—27, to either one or both filters 28—28. Thus by controlling the valves 27 either filter may be employed while the other is being cleaned. The water passes from either or both filters to a clear well 29.

Instead of introducing the softening reagent through the pipes 6 and 7 and thus mixing said reagent with the water before electrolyzing the water, it is obvious that

either or both of said pipes 6 and 7 may be connected with the influent pipe 5 at the point α between the electrolytic cell B and the sedimentation tank 23, as shown by the 5 dotted lines in Fig. 2.

The water in passing through the cell B is subjected to an intense electrolyzing current, and electrolysis of the salts occurs. Some acid ions liberated at the anode attack the latter, if made of aluminum or iron, and from corresponding salts which are dislodged and enter the body of the water. The basic ions liberated form hydroxides and likewise pass into the water. When 10 these two electrolytes blend they combine to form iron or aluminum hydroxides and re-establish the normal condition found before electrolysis. This hydroxide however serves as a coagulant for the water and 15 causes more rapid sedimentation, not only of the precipitated and suspended calcium and magnesium salts, but of other suspended matter as may have been present in the raw water. The tortuous passage 20 through the mixing chamber further serves as a mixing device for effecting diffusion and thorough intermingling of the reagents and the water without a special chamber for the purpose.

25 We have found however that with such a cell it is possible for polarization to occur i. e. in electrolyzing the salts, hydrogen and oxygen from the water are separated on the surface of the electrodes, thus diminishing their area and furthermore forming hydrogen and oxygen electrodes with a re-

sultant E. M. F. which interferes with the operation of the cell.

To avoid this undesirable feature, we place the water under sufficient pressure to 40 attain a velocity sufficient to sweep the electrodes clear of such globules as they form. Good results are obtained with a velocity of one and one-half feet per second.

The water thus treated passes into the 45 reaction and sedimentation tank or basin 23 in which the suspended and precipitated matters are deposited.

From the foregoing it is thought that the features and advantages of the present improvement will be readily understood by those skilled in the art and it will of course be understood that any suitable and convenient type of apparatus may be used to carry the invention into effect. 50

We claim:—

A process for aiding the chemical softening of water, which consists in injecting a softening reagent under pressure into the feed line, next predisposing the water under 60 pressure to rapid reaction by electrolysis, and subsequently conducting the chemically and electrically treated water through a relatively capacious sedimentation basin.

In testimony whereof we hereunto affix 65 our signatures in the presence of two witnesses.
